Primary Examiner — Richard E Chilcot*Assistant Examiner* — John Eberhart(74) *Attorney, Agent, or Firm* — NSIP Law(57) **CLAIM**

The ornamental design for a desktop computer, as shown and described.

DESCRIPTION

FIG. 1 is a top-front perspective view of a desktop computer, showing our new design;
FIG. 2 is a front view thereof;
FIG. 3 is a rear view thereof;
FIG. 4 is a left-side view thereof;
FIG. 5 is a right-side view thereof;
FIG. 6 is a top plan view thereof;
FIG. 7 is a bottom plan view thereof;
FIG. 8 is a top-rear perspective view thereof; and,
FIG. 9 is a partial view of FIG. 7 that is included to more clearly depict the design feature on the rear portion of desktop computer.

The broken lines are for environmental purposes only and form no part of the claimed design. The shade lines in the figures show contour and not surface ornamentation.
